UNITED STATES PATENT OFFICE.

OSCAR P. BUSHNELL, OF BELLEVILLE, NEW JERSEY.

ACCUMULATOR.

1,200,408.

Specification of Letters Patent.

Patented Oct. 3, 1916.

Application filed April 4, 1916. Serial No. 88,978.

To all whom it may concern:

Be it known that I, OSCAR P. BUSHNELL, a resident of Belleville, in the county of Essex and State of New Jersey, have invented 5 certain new and useful Improvements in Accumulators, of which the following is a specification.

In many branches of the industrial arts it is very desirable to vary the load on the 10 accumulator plunger, and consequently the pressure delivered by the accumulator, beginning with the lowest pressure and increasing the load and consequent pressure as the work progresses. In the manufacture 15 of paper board for example, it is objectionable to apply the full pressure all at once. To obtain the best results, it is the practice to apply the lightest pressure first to squeeze out a little water, and to allow 20 that pressure to remain for a certain length of time, then to increase the load and consequent pressure to squeeze out a little more water, and to allow that pressure to remain for a certain length of time, and so on step 25 by step, until the highest desired pressure is reached. So far as I am informed, however, hydraulic accumulators, as heretofore made, are built to give but one pressure, a pressure determined by the weight of the 30 dead load piled upon or carried by the accumulator plunger itself. Of course, by stopping the operation of the accumulator and increasing or diminishing its load, the pressure can be correspondingly increased 35 or diminished. But this, with the heavy weights which are employed, takes both time and trouble to accomplish, and as a rule is only practicable when the change is made not oftener than once or twice a day; 40 and even that is not infrequently too often to handle the heavy material of which the load is made up. For the purpose of obviating these and other objections, I have produced what may be termed a variable- 45 load accumulator, in which the increase in the load and consequent pressure is effected automatically at predetermined intervals and without stopping the operation of the accumulator, from the lowest pressure to 50 the highest pressure desired, through any intermediate pressures desired. This I believe to be broadly new with me.

To enable others skilled in the art to understand and use my invention, I will now proceed to describe the manner in which 55 the same is or may be carried into effect by reference to the accompanying drawings which represent a hydraulic accumulator embodying my invention in its preferred form. 60

In said drawings—Figure 1 is a plan view, largely diagrammatic, showing the pump (a quadruple high-pressure pump), the accumulator cylinder and plunger, and their connections. Fig. 2 is a section of the 65 operating valve X shown in Fig. 1. Fig. 3 is a side elevation, largely diagrammatic, indicating the connections between the pump actuating devices and the "timing" mechanism which determines the rate of 70 rotation of the "trip" shaft, as hereinafter more fully explained. Fig. 4 is a side elevation of so much of the accumulator structure as needed for purposes of explanation. This structure in practice is between thirty 75 and forty feet high, so that necessarily certain intermediate portions of the structure have been broken away and removed, in order to bring the figure, even at the reduced scale on which it is drawn, within 80 the limits of the sheet. Fig. 5 is an enlarged section on line 5—5 Fig. 4 of the structural steel uprights which form the guides between which the accumulator plunger and weights move, and to which the 85 bearings and supports for the mechanism for regulating the movements of the accumulator plunger and its associated parts are attached. In this view the "pawl" shaft 29 and "trip" shaft 40 are shown in horizontal 90 section with one of the pawl holders 30 and pawls 31 partly in section, and with the "trips" 39 in plan, showing their staggered arrangement on the "trip" shaft 40. The view also shows in plan the 95 staggered arrangement of the peripheral lugs 27 on the intermediate weight-section supports 24, and the rods 28 passing through and connected to said lugs, whereby each intermediate weight-section 100 support is suspended from the one next above; the same arrangement of the parts last named is shown in elevation on reduced scale in Fig. 3. The same is par-

tially shown in elevation on larger scale in Fig. 4, together with the "timing" mechanism and the "pawl" and "trip" shafts. Figs. 6, 7 and 8 are detail views on enlarged scale of the "timing" mechanism. Fig. 6 is a sectional elevation of said mechanism on enlarged scale with the "clutch lock" 53 lifted out of engagement with the "clutch disk" 52. Fig. 7 is a section on line 7-7 Fig. 6. Fig. 8 is a detached elevation of the "clutch disk" 52 with the "clutch lock" 53 dropped into engagement therewith. Figs. 9-13 inclusive, have to do more particularly with the mechanisms for operating the "safety" or relief valve 15, and show on a like enlarged scale the structural details of the same. Fig. 9 is a sectional plan, showing one of the steel I-beam uprights 2, with a portion of the bottom weight support 1, together with one of the pawl holders 30, and pawls 31, and one of the trips 39—the parts last named being shown in full lines in the position they occupy when the pawl 31 overhangs the tang T on the bottom weight support 1, and in dotted lines in the position which they occupy when the trip 39 in its revolution has engaged the pawl holder 30 and has swung it far enough around to carry the pawl 31 out of the path of the tang T. Fig. 10 is a side elevation of these parts, with the pawl holder 30 and centering collar 34, partly broken away to expose interior structural details. In this figure the bottom weight support 1 is shown in dotted lines as just passing the pawl 31, during its descent from its highest position to the low position from which it originally started, and the pawl is shown in dotted lines in tilted position to permit of this descending movement of the bottom weight support 1. Fig. 11 is an elevation of the pawl shaft with one of the pawl holders (with pawl removed) partly in section, the parts being in the position they occupy when the safety valve 15 is in closed position. Fig. 12 is a similar view with the parts in the position they occupy when the safety valve is lifted and the pawl holder has been swung to one side so that its pawl (not shown) will be just on the point of disengaging from the tang T on the bottom weight support. Fig. 13 is an enlarged diagram showing the centering collar 34 in elevation, and the path of the pawl holder in rising from its seat in the centering collar, thence swinging to one side to clear the bottom weight support 1, and thence dropping back into its seat to which it is directed by the converging inclines 35 of the centering collar.

In the diagrammatic Fig. 1, 1 is the bottom weight support, which in practice is connected to and moves with the accumulator plunger crosshead (not shown) between the structural steel uprights 2 of I cross sec-

tion; 3 is the accumulator cylinder and 4 is the plunger; 5 is the quadruple high pressure pump drawing its supply from tank 6 through pipe 7 and discharging it into the accumulator cylinder through pipe 8 and its connections 9, 10; 11 is the pipe through which pressure from the accumulator is conveyed to the "press" where it is to be utilized; 12 is a check valve in pipe 9 which opens to the pump pressure but closes against back pressure from the accumulator; a cock 13 in pipe 11 controls a discharge 13^a leading back to the tank 6; from pipe 10 leads a pipe 14 back to the water supply tank 6, said pipe having in it a "safety" or "relief" valve, 15, operated and controlled by means hereinafter described, and normally closed against either accumulator pressure or pump pressure, but which when opened will permit circulation both from pump and accumulator through the pipe 14 back to the tank, thus preventing any further increase in pressure, and consequently any further rise of the accumulator plunger, so long as it is open. The pump gets its movement from any suitable prime mover, 16, 16^a indicating the fast and loose pulleys to which a driving belt is led from the prime mover. As shown in Fig. 3, the fast one 16, of these pulleys has on its hub a pinion 17 which meshes with a gear wheel 18 on crank shaft 19 from which the high pressure pump units 5 are driven.

The "operating" valve X and its connections shown in Figs. 1, 2, 3, are designed mainly to connect the "trip" shaft with, and disconnect it from, the "timing" mechanism by which it is rotated, and will be hereinafter described in connection with the parts last named.

When the high pressure pump is in action it will act to lift the accumulator plunger until the "safety" or "relief" valve 15 is opened, when further increase of pressure, and consequent rise of the plunger, is prevented, although the pump still continues in action. The moment the valve 15 closes, the accumulator plunger will again take up its upward movement, and thus, without shutting down the pump, the upward movement of the plunger and weight or weights carried by the same, can be stopped and resumed at will. This much by way of general explanation. I shall now proceed to describe more particularly the construction and arrangement of the frame and the operating parts of the accumulator, and especially those parts by which the operation of the "safety" valve is automatically controlled, and by which the plunger at each upward stage of its movement at predetermined intervals of time is caused to automatically pick up additional weight as required.

3 is the vertical accumulator cylinder,

mounted in or on, and supported by, a suitable base structure; 4 is the plunger which works up and down in the same. The cylinder is of course provided at the top with 5 the customary stuffing box to make a tight joint with the plunger which works through it. To the top of the plunger is secured the crosshead 20, the ends of which fit in the channels of the uprights 2 which constitute 10 guides for assuring the crosshead in its up and down movements. The uprights are held and supported in proper position by a skeleton tower-like structure 21, wherein they are properly secured. Connected to 15 and moving with the crosshead is the lowermost or bottom weight support 1, shown on enlarged scale in Fig. 1, having peripheral guide fins 22, which enter and move in the guide channels in the interior opposite faces 20 of the two uprights 2. The connection between the crosshead and bottom weight support consists of four vertical rods 23 which extend between, and pass through holes in, the crosshead and bottom weight support 25 respectively, and are there held by nuts on their projecting screw-threaded ends.

Above the bottom weight support is a series of weight-section supports, as they may be called, 24, located one above the 30 other at proper intervals apart, and each designed to receive an individual unit or section of the whole load. These weight-section supports, however, while provided, like the bottom weight support, with peripheral guide fins to fit in the channels of the uprights between which they are designed to move, are not connected, like the bottom weight support, to the plunger crosshead, but the topmost weight section support 24 35 is suspended from brackets 25 secured to the uprights 2 by four rods 26 which pass through suitable holes in the brackets and in peripheral lugs or projections 27 on the suction support respectively, and are there 40 held by nuts on their screw-threaded ends as shown. The intermediate weight-section supports—that is to say, those between the topmost support 24, and the bottom weight support 1—are suspended, each from the 45 section support next above, by rods 28 applied and arranged similarly to those already described, each weight-section support 24 having two sets of holes—four in each set—formed in peripheral lugs 27 suitably 50 placed or staggered so that the rods, when nested as hereinafter described, will not interfere with one another, as indicated in Fig. 3—the one set of holes being for the rods 28 by which it is suspended from the 55 weight-section support next above, the other being for the rods 28 from which is suspended the weight-section support next below. The eyes or holes which receive the rods by which the support is suspended fit 60 the rods loosely to an extent which will per-

mit the support to move up and down on the rods. The distance between any adjoining two of the weight-section supports will be determined by the length of the rods which will connect them. 70

I have shown on one or two of the weight-section supports 24 a load composed of removable weights W, which are made sectional, so that they may be piled up on the support without interfering with the rods 75 23 which connect the plunger crosshead and the bottom weight support 1, and which, of course, will pass up loosely through the intermediate weight-section supports 24. Under this arrangement it will be seen that 80 as the accumulator plunger is forced upward by the pressure in its cylinder, it will carry with it the bottom weight support 1, which as it rises will pick up in succession each weight-section support 24, and the individual weight-section unit W which it carries, the intervals of time between the picking up of successive section-weight supports 24, and the consequent increase in the load, depending upon the rate of upward 85 movement of the plunger, and the length of the rods 28 which connect a given support 24 below with the support 24 next above. I now proceed to a description of 90 the mechanism by which the movement of the accumulator plunger for this purpose is governed and controlled.

Supported in suitable bearings attached to one of the uprights 2 is a vertical shaft 29, attached at its lower end to the stem 100 of the safety valve 15 (shown in section in enlarged Figs. 11, 12). The shaft 29, which I shall call the pawl shaft, is capable of vertical movement in its bearings of sufficient range to permit it to lift the safety 105 valve far enough to open the port in the pipe 14 (Fig. 1) which it controls. The means for thus lifting the pawl shaft comprise a projecting tang T on the periphery of the bottom weight support 1, and a series 110 of detent devices, each consisting of a pawl holder 30, and a pawl 31, pivoted in said holder on a horizontal axis 32—these parts with other parts associated therewith being shown on enlarged scale and in detail 115 in Figs. 9-13.

The pawl holder is mounted loosely upon the pawl shaft 29 so that it may both swivel and move up and down on the same; and it is held in place thereon between the adjustable set collar 33 above, and the centering collar 34 below, which latter is formed with two downwardly converging inclines 35, which at their point of meeting furnish a seat for the pawl holder, said pawl holder 120 being furnished at that point with a friction roller 36 which rests in the seat thus formed, as indicated in Fig. 11—this being the normal position of the pawl holder. The distance between the collars 33 and 34, as 125

indicated in Figs. 11 and 12, is sufficiently greater than the height of the pawl holder 30 to furnish clearance to permit the latter to be lifted high enough to clear the top 5 of the centering collar 34 by the time it contacts with the set collar 33 above—at which point it can swivel or swing upon its shaft 29 without being interfered with by the centering collar 34. The swiveling of 10 the pawl holder permits it to be swung around to carry its pawl 31 out of engagement with the tang T; and, after being thus released, it drops back to its seat in the centering collar, being guided to proper 15 place by the passage of its roller 36 over the converging inclines 35.

The nose of the pawl 31, which is armed with a friction roller 37, normally overhangs and lies in the path of movement of 20 the tang T of the bottom weight support 1, so that when the latter rises said tang will meet friction roller 37 in the nose of the pawl—this friction roller 37 serving to facilitate the swinging movement of the pawl 25 by which it is disengaged from the tang T. A series of these pawls and their holders are thus-mounted and held upon the pawl shaft, one above the other, in number corresponding to the number of increased pressures 30 to be delivered by the accumulator; and normally the noses of the pawls are in one and the same vertical line, so that, as the bottom weight support 1 rises, its tang T will meet the several pawls in succession. 35 In the normal position of the pawl its weighted heel rests upon a ledge 38 in the pawl holder, which enables the pawl to take and sustain, without tilting, the upward thrust of the tang T as the latter rises. 40 Thus when the tang in its upward movement reaches and contacts with the pawl, it will lift the pawl and pawl holder bodily through the clearance space above until the pawl holder brings up against the upper 45 set collar 33 on the pawl shaft 29, after which continued upward movement of the tang T will, through the intermediary of the pawl and pawl holder, lift the pawl shaft 29 with the effect of opening the safety 50 or relief valve 15, which, as hereinbefore stated, arrests further upward movement of the accumulator plunger and the bottom weight support 1 attached to the same, and permits the pressure thus far accumulated 55 to be made use of. The horizontal dotted lines x, y, z, between the upper parts of Figs. 11 and 12, indicate diagrammatically this upward movement of the pawl holder, the distance between x and y representing 60 the clearance to be traveled by the pawl holder in rising from its position in Fig. 11 to the set collar 33, and the distance between y and z representing the subsequent extent of movement of the pawl holder by

which the pawl shaft is lifted to open the 65 valve 15.

To permit the upward movement of the plunger and its attached bottom weight support to be automatically resumed at the proper time with the consequent taking on 70 of additional weight, I make use of a series of trips 39, one for each pawl holder, mounted fixedly but adjustably upon a vertical rotating shaft 40—the “trip” shaft—which is mounted and supported in suitable 75 bearings and arranged parallel with the pawl shaft 29. Each trip revolves with the shaft 40 and is secured thereon in such position as, during its rotary movement, to meet at the proper time its appropriate pawl 80 holder 30 and to swing it to one side far enough to cause its pawl 31 to clear and disengage itself from the tang T, as indicated by dotted lines in Fig. 9. The pawl holder is formed for this purpose with an arm 41 which extends into the path of rotation of the trip 39, and at the point where it meets the trip, is provided with a roller 42 to reduce friction.

As soon as pawl 31 swings aside far 90 enough to clear tang T, the pawl shaft at once drops, thus closing the safety valve, and again delivers the pump pressure to the accumulator with the effect of causing bottom weight support 1 to resume its upward 95 movement until its tang T brings up against the pawl next above, when the operation just described is repeated, and so on. The pawl shaft in dropping to close the safety 100 valve of course carries with it the pawl and pawl holder thus disengaged from the tang T. After the shaft has come to rest, however, the descending movement of the pawl and pawl holder will still continue, independently of the shaft, through the clearance space—which at this time is between the pawl holder and the centering collar 34 below, as indicated in Fig. 12—until the pawl holder brings up in its seat in the said 110 collar, to which seat it is directed during this descending movement by the converging inclines 35. The course of the pawl holder in thus rising from and returning to its seat, is indicated diagrammatically by the arrows in Fig. 13.

The rotary movement of the trip shaft is obtained from what I term a “timing” mechanism, which is designed to drive said shaft at a measured and very slow rate of rotation. The parts of this mechanism are 120 mounted in a bracket frame 43 secured in proper position to one of the I-beam uprights of the main frame, said bracket frame also containing the upper trip shaft sleeve-like holder or bearing 44, up through which 125 the trip shaft extends, as shown in Fig. 6. Supported in suitable bearings in frame 43 is a horizontal worm shaft 45 driven by any

- suitable means—in this instance getting its movement from the wheel 18 on the crank shaft 19 by which the pump units are driven, as indicated in Fig. 3, through the intermediary of a belt 46 passing from a pulley 47 on the hub of wheel 18 to a pulley 48 on the outer end of the worm shaft 45. Worm shaft 45 gears with and drives a worm gear 49 mounted in proper bearings in bracket 10 frame 43 and having on its hub a worm 50 which in turn meshes with and drives a properly mounted worm gear 51 revolving loosely upon the trip shaft 40 which passes axially up through it.
- 15 Connection is made between the worm gear 51 and the trip shaft by means of a clutch mechanism consisting of a clutch disk 52 keyed on the trip shaft and located between the trip shaft holder or bearing 44 20 and the slowly revolving power driven worm gear 51—said clutch disk having an annular ratchet-formed upper face, as shown in Figs. 7, 8. To coöperate with the clutch disk I provide a clutch lock or grab 25 53, the cylindrical stem of which passes down through a similarly formed eccentrically located opening in the worm gear 51, in which opening the clutch lock or grab, while revolving with the gear can slide up 30 and down away from and toward the ratchet toothed face of the clutch disk below. When lowered, its toothed lower end engages the clutch disk, thereby causing the trip shaft to revolve in unison with the 35 worm gear 51; when raised, it will be lifted out of engagement with the clutch disk, whereupon the rotary movement of the trip shaft will cease. Any suitable means for thus manipulating the clutch lock may be 40 employed. In the arrangement for the purpose shown in the drawing, the stem of the clutch lock is secured to a cap 54—a “clutch lock” cap—which fits over and down upon the upper end of the trip shaft 40, on which 45 it can both swivel and move up and down. The “clutch lock” cap 54 is swiveled upon the lower end of a vertical eye-bolt 55 attached to and suspended from one end of a rope 56 which passes over suitable guide 50 pulleys 57 to a weight 58 which draws the rope in a direction to lift the “clutch lock” cap and consequently raise the clutch lock or grab 53 out of engagement with the clutch disk 52, in which position the parts 55 are shown in Fig. 6. On the other hand if the weight 58 be lifted to give sufficient slack to the rope, the “clutch lock” cap, and consequently its attached clutch lock 53, will drop far enough to engage the latter with 60 the clutch disk, in which position the clutch lock is shown in Fig. 8. For the purpose of thus manipulating the weight 58, various means may be employed. One convenient means for the purpose is shown in the drawing. The weight 58 is mounted upon 65 a plunger 59 adapted to work up and down in a cylinder 60 connected by suitable piping as shown with some source of supply of water under pressure—a low pressure accumulator for instance; the flow of water 70 from the source of supply to the cylinder 60 is controlled by a valve 61 in X, shown in section in Fig. 2. In the position in which the operating handle 62 is there shown, connection of the cylinder 60 with the source 75 of supply (“inlet”) is cut off by the valve 61. Throwing the handle from this position to the left will put the valve in position to place the cylinder and inlet ports into communication with the effect of lifting the plunger 59 and consequently the weight 58; throwing the handle from this position to the right will put the cylinder and discharge ports into communication, thus allowing the plunger 59, and consequently the weight 58, to descend. The movement of the plunger downward, or in a direction to cause the “clutch lock” to be disengaged from the clutch disk 52, will also, through suitable intermediary mechanism (as indicated diagrammatically at 63 in Fig. 1), actuate a belt shifter S to shift the driving belt from the fast pulley 16 to the loose pulley 16^a, thus stopping the pump 5, and also the timing mechanism. 95
- It is desirable that after the conclusion of the operation the trip shaft shall be returned automatically to its original position. To this end (as shown in Fig. 3) a weight 64 is suspended from a rope 65 which passes 100 up over a properly housed peripherally grooved guide pulley 66 to a sheave 67 mounted on and fast to the trip shaft 40, to the periphery of which sheave it is secured. Under this arrangement, when the 105 trip shaft is engaged with and rotated by the timing mechanism, the rope 65 will be wound up on the sheave which revolves of course with the trip shaft. When, however, the trip shaft has completed its work and is 110 disengaged from the timing mechanism, the weight 64, acting through the rope 65 and the sheave 67 upon which the rope has been wound, will rotate the trip shaft in the opposite direction and return it to its original 115 position.
- The highest pressure is delivered when the tang T of the bottom weight support 1 reaches the topmost pawl 31, and through its agency and that of its holder 30 lifts the 120 pawl shaft 29 and opens the “safety” or relief valve 15, thus arresting the further upward movement of the accumulator plunger. It will be noted, however, by reference to Fig. 4, that there is, on the trip shaft, no 125 trip 39 to coöperate with this topmost pawl holder and pawl; and therefore the bottom weight support 1, and its superimposed load,

will remain at this point and continue the delivery of the final and highest pressure to the "press" indefinitely, or until released by some means. It is for this purpose that the 5 manually operated discharge valve or cock 13 is provided, and this valve or cock is preferably located in the immediate vicinity of the "press", as shown, so that it may be conveniently reached and manipulated by 10 the operator in charge of the "press"— which, it may be said, is not infrequently located at quite a distance from the place where the accumulator and the high pressure pump are housed. This operator maintains 15 the highest pressure upon the material operated on in the "press" for such length of time as he may deem necessary; and then, the work having been completed, he opens the discharge cock 13, thus relieving the 20 pressure and drawing off the water from the accumulator and the "press" and the system of piping connecting them, and returning it to the tank 6. This maintenance of the highest pressure is in no wise dependent 25 upon the continued action of the pumps and "timing" mechanism, both of which (through the operating valve X and its connections) can be stopped without affecting the continuance of the pressure in the interconnected accumulator and "press" system, which, as hereinbefore explained, will be maintained until the attendant at the "press" 30 station opens the valve 13.

It will be noted that there are but two 35 manually operated valves in the whole system, the operating valve X at the accumulator and pump station, for stopping and starting the pump and the "timing" mechanism, and the discharge cock 13 at the "press" station, to relieve the pressure in the accumulator and "press" system, and to drain the water from that system. It will also be noted that all 40 of the intermediate pressures between the initial and the highest pressures are automatically controlled with precision and indeed absolute exactitude by the mechanism immediately associated with the accumulator—that is to say, the "timing" mechanism and the pawl and trip systems. This 45 is an important function of the accumulator.

The accumulator cylinder and the "press" cylinder, and their interconnecting system of piping, have a common communication with the pump, so that at all times during 55 the operation of the pump the pressure is equalized throughout the accumulator and "press" system. The pump continues in operation from start to finish, and the effect of opening the safety valve 15 at any pre-determined intermediate point during the 60 ascent of the plunger, is merely to arrest the movement of the plunger at that point, the excess water delivered by the pump beyond that required to maintain the pressure

needed to hold the plunger at that point, returning through the bypass 14, and the now open safety valve 15 controlling the same, back to the tank 6.

The "timing" gearing may be so proportioned and have such initial speed, as to enable it to impart any predetermined speed of rotation to the "trip" shaft. In the actual timing mechanism, from which the representation in the drawing is taken, each one of the worm gears had 63 teeth, thus causing 70 the second worm gear 51 to make one revolution for $63 \times 63 = 3969$ revolutions of the first worm shaft 45. These figures may be varied as desired, but the revolution of the trip shaft must in any event be very slow, 75 inasmuch as all the trips which are to act on the pawl shaft must do so during substantially one revolution, at the outside, of the trip shaft—the trips being set each in the position required to enable it to reach 80 and act upon its pawl holder at the proper time after the next preceding trip has acted on its pawl holder. The staggered arrangement for this purpose of the trips upon the trip shaft, is indicated in plan—to some extent diagrammatically—in Fig. 5.

In my variable load accumulator, as before remarked, the operations of stopping, restarting, taking on additional weight, again stopping, and so on, are automatically 95 conducted and controlled. This I believe to be broadly new with me, beyond the particular mechanism and devices herein shown and described by me for these purposes; although I prefer said mechanism and devices as being in practice the best adapted, on the whole, to effectuate my invention. I remark also that I am not aware of any hydraulic pressure accumulator, prior to mine, in which there is any provision which would 100 permit a plurality of weight sections to be automatically picked up, each in turn, by and during the ascent of the plunger, and then, during the descent of the plunger, to be automatically returned and dropped, one 105 by one, into the respective positions from which they were originally taken. By the term "weight-section" I of course intend a weight-section support 24, along with the individual initial load W, whatever it may 110 be, that is associated with it. In conclusion, therefore, I would state that I do not confine myself strictly to the structural embodiment of my improvements as hereinbefore 115 described and illustrated in the drawings, 120 since manifestly the same can be varied considerably without departure from the spirit of my invention: but

What I claim herein as new and desire to 125 secure by Letters Patent, is as follows:

1. An accumulator comprising a cylinder; a plunger adapted to work up and down therein; a bottom weight support connected

to and moving with the plunger; a plurality of weight-sections located, one over the other, above, and in the path of movement of, the bottom weight support; means for suspending each weight-section from the one next above, and permitting movement of the thus-suspended weight-section to and from the weight-section above; and a stationary support from which the topmost weight-section is suspended—these parts being combined and arranged for joint operation substantially as described, whereby said weight-sections will be automatically picked up, each in turn, by the bottom weight support during the ascent of the plunger, and then, during the subsequent descent of the plunger, will be automatically returned and dropped, one by one, into the respective positions from which they were originally taken.

2. The combination with the accumulator cylinder and plunger, the bottom weight support connected to and moving with the plunger, and the plurality of weight-sections located, one over the other, above, and in the path of movement of, the bottom weight support, and arranged and adapted to be successively picked-up by said bottom weight support during the ascent of the plunger; of means for automatically arresting the upward movement of the plunger after the taking-on of each additional weight-section; and means for automatically, and at a predetermined time, releasing the thus-arrested plunger and permitting it to resume its ascent, substantially as and for the purposes hereinbefore set forth.

3. The combination with the accumulator cylinder and plunger, the bottom weight support connected to and moving with the plunger, and the plurality of weight-sections located, one over the other, above, and in the path of movement of, the bottom weight support, and arranged and adapted to be successively picked-up by said bottom weight support during the ascent of the plunger; of means for automatically arresting the upward movement of the plunger after the taking-on of each additional weight-section; means for automatically, and at a predetermined time, releasing the thus-arrested plunger and permitting it to resume its ascent; and manually operated means for relieving the pressure in the accumulator cylinder after the plunger has completed its ascent, and permitting the latter and its attached bottom weight support, together with the weight-sections superimposed on the same, to descend to the positions from which they respectively started, substantially as and for the purposes hereinbefore set forth.

4. The combination of the accumulator cylinder and plunger; a crosshead attached

to the plunger; a bottom weight support; 65 rods connecting the plunger crosshead with the bottom weight support; a topmost weight-section support, and suspensory rods for the same attached to the machine frame; a plurality of weight-section supports intermediate the topmost weight-section support and the bottom weight support; rods whereby each intermediate weight-section support is suspended from the one next above; and vertical guide ways in the frame for said 70 crosshead and supports, substantially as and for the purposes hereinbefore set forth.

5. The combination of the accumulator cylinder and plunger; the bottom weight support connected to and moving with the 80 plunger and provided with a laterally projecting tang; the pumps and the supply pipe leading therefrom to said cylinder and having a waste or relief outlet; a normally closed safety or relief valve controlling said 85 outlet, a vertical pawl shaft supported in proper bearings in which it can be moved up and down, and connected to and adapted to operate said valve; a pawl holder mounted, and adapted to swivel, and to 90 move up and down, on said shaft; a set collar and a centering collar fixed on the shaft and serving to limit said up and down movement of the pawl holder which is located between them; a pawl pivoted in 95 said pawl holder with its nose in the path of the laterally projecting tang on the bottom weight support, adapted to resist the upward thrust of said tang, but to tilt downwardly out of the path of the 100 tang when pressed on from above; a trip shaft and means for rotating the same at measured speed; and a trip fixed on and revolving with said trip shaft, and adapted at a predetermined time after the tang has 105 engaged the pawl and lifted the pawl shaft, thus opening the relief valve and arresting further upward movement of the plunger, to meet the pawl holder and to swing it in a direction to disengage its pawl from the 110 tang, thus permitting the pawl shaft to drop, the relief valve to close, and the plunger and bottom weight support to resume their upward movement, substantially as and for the purposes hereinbefore set forth. 115

6. In an accumulator of the character described, the combination with the vertical pawl shaft and series of pawl holders and their contained pawls mounted thereon; of the trip shaft supported in proper bearings 120 in a position parallel with and in proximity to the pawl shaft; a series of trips mounted thereon, each adapted to cooperate with its appropriate pawl holder on the pawl shaft; driving mechanism for rotating the 125 trip shaft at measured speed; and means for engaging said driving mechanism with, or disengaging it from, the trip shaft at will.

7. In an accumulator of the character described, the combination with the vertical pawl shaft and series of pawl holders and their contained pawls mounted thereon; of the trip shaft supported in proper bearings in a position parallel with and in proximity to the pawl shaft; a series of trips mounted thereon, each adapted to coöperate with its appropriate pawl holder on the pawl shaft; 10 driving mechanism for rotating the trip

shaft at measured speed; means for engaging said driving mechanism with, or disengaging it from, the trip shaft at will; and means whereby the trip shaft, when disengaged from its driving mechanism, is automatically returned to the position from which it started its rotary movement.

In testimony whereof I affix my signature.

OSCAR P. BUSHNELL.
